UNITED STATES PATENT OFFICE.

JOHN A. CARLAW AND MICHAEL J. TEEDY, OF TORONTO, CANADA; SAID TEEDY ASSIGNOR TO SAID CARLAW.

BAG FOR TRANSPORTING MONEY, &c.

SPECIFICATION forming part of Letters Patent No. 513,756, dated January 30, 1894.

Application filed March 23, 1893. Serial No. 487,313. (No model.)

To all whom it may concern:

Be it known that we, JOHN ANDERSON CARLAW and MICHAEL J. TEEDY, of the city of Toronto, in the county of York and Province 5 of Ontario, Canada, have jointly invented a certain new and Improved Bag for Containing Moneys or other Valuables for Transmission from One Place to Another, of which the following is a specification.

10 The object of the invention is to design a bag which can be readily and effectually closed so as to render it impossible to be opened without leaving visible traces of its having been tampered with, and it consists, 15 essentially, of a bag of canvas or other pliable material having on one side of its mouth a strip of stiff leather or other suitable material the said mouth being closed by bringing one side of the mouth against the side having 20 the stiffening piece, and folding the two together over and down against the side of the bag securing it thus double folded by a cord or its equivalent laced in holes pierced through the stiffened strip and sides of the bag, substantially as hereinafter more particularly explained and then definitely claimed.

In the accompanying drawings Figure 1, is a view of our bag before the mouth is closed. Fig. 2, is a view of the bag with the mouth 30 closed in accordance with our invention. Fig. 3, is a view similar to Fig. 2, except that the seal is placed on top of a tag instead of the cupped-shaped seal receptacle.

We preferably bind the mouth of the bag 35 A, with pliable leather binding B, about twice the width of the strip C, which is preferably made of stiff leather and in length corresponds with the width of the bag A. This strip C, is sewed or otherwise securely fastened to the mouth of the bag A, and acts as a stiffener to prevent the mouth so protected being crumpled or opened. A row of holes D, 40 is made through the strip C, and a corresponding row of holes E, is made through the binding B, immediately opposite to and corresponding with the holes D. A third row of holes F, is also made through the binding

B, which pass through both sides of the bag at the point indicated.

In order to close the mouth of the bag, its 50 two sides a and b are brought together so that the holes D and E come opposite each other, and the whole mouth of the bag is folded until the folded part lies parallel with the body of the bag and so that said strip will be on 55 the outside and the holes D and E register with the holes F, as indicated in Figs. 2 and 3. A cord G or its equivalent is then laced through the holes D, E, and F, and the ends of the cord G, so laced are brought together 60 and fastened by a seal H. This seal we prefer to make of wax in a metal cup I, which we rivet to the strip C, and pierce to permit the cord G, being threaded through it. This cup will effectually prevent the seal H, being 65 tampered with, as it will be utterly impossible to remove the seal for the purpose of getting at the cord without utterly destroying the said seal. The cup I, will also protect the seal from being injured by rough handling. 70

Although we prefer the employment of a cup I, as we consider it an additional safe guard, it may be dispensed with and the seal H, placed directly onto the strip C, or as shown in Fig. 3, on top of the tag J, on which 75 a memorandum of particulars is printed.

From this description it will be seen that we secure a bag which cannot possibly be opened without exhibiting evidence of its having been tampered with.

8c

What we claim as our invention is—

1. A bag having two rows of perforations through each of its sides, one row in its body and the other near its mouth, and a strip of stiff leather or other material secured to one 85 side of said bag, and having perforations therein arranged to register with the perforations in the bag when the mouth of said bag is shut and folded, whereby the bag can be securely fastened by a cord passing through 90 said perforations, substantially as described.

2. A bag having two rows of perforations through each of its sides, one row in its body and the other near its mouth, and a strip of

stiff leather or other material secured to one side of said bag, and having perforations therein arranged to register with the perforations in the bag when the mouth of said bag is shut and folded, in combination with a metal casing secured to the stiffening strip and pierced to receive a cord, whereby the bag is fastened by a cord passing through said perforations and sealed by the cord pass-

ing into the sealing material in said casing, to substantially as described.

Toronto, March 9, 1893.

JOHN A. CARLAW.
MICHAEL J. TEEDY.

In presence of—

A. M. NEFF,
